UNITED STATES PATENT OFFICE.

LAWRENCE E. JOHNSON, OF WINTHROP, MASSACHUSETTS.

SOLE ROUGH-ROUNDING AND CHANNELING MACHINE.

1,149,369.

Specification of Letters Patent. Patented Aug. 10, 1915.

Application filed March 27, 1915. Serial No. 17,946.

To all whom it may concern:

Be it known that I, LAWRENCE E. JOHNSON, a citizen of the United States of America, and a resident of Winthrop, in the county of Suffolk and State of Massachusetts, have invented certain new and useful Improvements in Sole Rough-Rounding and Channeling Machines, of which the following is a specification.

10 This invention relates to sole rough rounders and channeling machines to be used in the manufacture of boots and shoes, and is an improvement over the machine shown and described in Letters Patent No. 15 1,125,550, issued to me January 19, 1915.

One objection to the machine shown in my earlier patent was that the work was inverted during the operation of the machine, and the operator found difficulty in 20 cutting the sole satisfactorily.

One of the objects of the present invention is to produce a machine in which the cutting may be done with the shoe right side up so that the operator will find it 25 easier to cut the sole the required distance from the upper.

Another object of the invention is to provide a machine of this character with a plurality of gages and clamping devices easily 30 adjustable whereby the work may be held in any desired position during the cutting of the sole.

The invention further consists of certain novel features of construction and arrangement of parts which will be fully understood by reference to the description of the drawings and to the claims hereinafter given.

Of the drawings: Figure 1 represents a 40 front elevation of a machine embodying the principles of the present invention. Fig. 2 represents a side elevation of the same. Fig. 3 represents a plan of the same. Fig. 4 represents an enlarged sectional detail 45 showing the relation of cutting devices to the work during the operation of the machine, Fig. 5 represents a perspective view of the work support and the channeling knife carried thereby, and Fig. 6 represents 50 a horizontal section of a portion of the machine, showing the slide in which the knife plate is mounted and the means for operating said slide.

Similar characters designate like parts

throughout the several figures of the drawings.

In the drawings, 10 is the base of a frame 11 having bearings 12 in which is revolvably mounted a shaft 13 adapted to be driven by a pulley 14. The shaft 13 has secured thereto the cam disks 15 and 16 which revolve therewith. The cam disk 15 is provided with a peripheral cam projection 17 adapted to coact with a roll 18 in the lower end of the lever 19 and move said lever about its pivot 20 thereby moving the upper end 21 of said lever toward the frame 11. This upper end 21 of the lever 19 has a curved bearing surface contacting with the stud 22 movable endwise in the eccentric 60 sleeve 23 mounted in a bearing in the frame 11. A lever 24 is secured to the opposite end of said stud 22 by means of a nut 25 threaded to the reduced end of said stud. The rear end of said lever 24 has adjustably 65 secured thereto a hook 26 between which and an eye 27 on the frame 11 is interposed a spring 28. The tension of the spring 28 may be adjusted by the regulating nut 29.

The eccentric sleeve 23 has clamped thereto an arm 30 provided with a handle 31 and having a projection 32 normally held against a stop member 33 extending laterally from the side face of the frame 85 11. When the eccentric sleeve 23 is moved about the axis of its bearing in the frame 11 by means of the handle 31 the friction thereon is sufficient to retain it in such adjusted position.

The spring 28 normally retains the forward end of said lever 24 against the stop projection 32 which limits the upward movement of said forward end. The stud 22 is provided with a head between which 90 and the frame 11 is a spring 33 a which retains the roll 18 in contact with the periphery of the cam disk 15.

The forward end of the lever 24 has secured thereto a block 35 having a threaded shank 36 extending through an opening in said forward end of the lever 24, the end of said shank having threaded thereto a nut 37. The shank 36 has a laterally extending pin 38 positioned in a slot 39 in the inner 100 face of said lever 24, thereby limiting the movement of the block 35 about the axis of its supporting shank 36 during the opera- 105

tion of the machine. Another block 40 is secured to the block 35 by means of the bolt 41 and between these two blocks 35-40 is clamped the channeling knife 42 having its upper end 43 bent toward the front of the machine.

The blocks 35-40 form the work support and carry the channeling knife 42, and all these members conform to the lateral movement of the lever 24. Coacting with the work support 35-40 is a presser foot 44 secured to a stud on an eccentric 45 positioned in a bearing 46 at the top of the frame 11. The eccentric 45 is provided with an operating handle 47 by which the eccentric may be moved about its axis, a spring 48 being provided to create sufficient friction to retain said eccentric in its adjusted position.

The rear end of the presser foot lever 44 is curved to form a cam surface as at 49 with which coacts a projection 50 on a lever 51 pivoted at 52 to the frame 11. This lever 51 is also provided with a lifting toe 53 normally against a stop member 54 but adapted to be moved against the rear end of the lever 24 to depress the work support against the tension of the spring 28.

The rear end of the lever 44 is provided with a vertical slot 55 in which is positioned a pin 56 secured in a lug 57 formed on the frame 11 and surrounded by a spring 58 which forces the operating end of the presser foot lever 44 into contact with the work.

35 The front of the frame 11 is provided with a grooved guide block 59 in the groove of which a plate 60 is adapted to reciprocate, said plate having secured to its upper end a chisel knife 61.

40 The lower end of the plate 60 is pivotally connected to one end of a link 62, the opposite end of which has clamped thereto an eccentric sleeve 63 mounted upon a stud 64 eccentrically positioned in the cam disk 16.

45 Above the knife 61 is an operating table 65 with which said knife coacts, the front edge of which serves as a gage, the welt of the shoe being held against this edge during the operation of the machine.

50 By unclamping the sleeve 63 and turning it in its bearing in the link 62, the knife 61 may be adjusted so that it will properly coact with the table 65 when shortened by being repeatedly sharpened. The block 59

55 is secured by means of the studs 66 to the slide 67 bearing in the frame 11. One end of the slide 67 is pivotally connected to the upper end of the lever 68 pivoted at 69 and having at its lower end a roll 70 in the cam path 71 in the back of the cam disk 16. The rotation of the cam disk 16 causes the cam 71 to act upon the roll 70 and impart a lateral movement to the knife 61 by means of the slide 67 and the guide block 59 secured thereto.

The operating table 65 is secured to the under face of the forward extension 72 by means of the securing members 73, thus making it possible to quickly remove said table 65 and replace it with another when the table which has been in use becomes inoperative.

When it is desired to insert new material, the presser foot may be raised by moving the lever 51 toward the front of the machine, the projection 50 traveling along the cam surface 49 moving the presser foot lever 44 about its pivot while at the same time the work support 35-40 is lowered by the action of the toe 53 upon the lever 24.

By means of the handle 31 the work support 35-40 may be moved toward or from the front of the machine and the knife 61 so that the soles may be cut at various distances from the upper as desired.

When the machine is in operation the end of the presser foot 44 is adjusted for the proper width of welt and the welt of the shoe is pressed against this edge of the table 65 as shown in Fig. 4, the knife 61 in its upward movement coacting with the edge of the table 65. It is obvious that the distance between the end of the presser foot 24 and the knife 61 may be adjusted by changing the position of the eccentric 45 by means of the handle 47.

When the machine is in motion, the knife 61 is forced through the outsole, the work support 35-40 with the channeling knife 43 moves to the right of Fig. 1, cutting a portion of the channel and then the work support and the knife 61 move toward the left, feeding the material. The knife 61 then descends from the sole, moves to the right and then again ascends into the material. The operation is continued in this manner, the operator retaining the shoe in engagement with the end of the presser foot and turning it at the toes to properly present the work to the cutting members. During the operation the work support 35-40 is movable slightly about the axis of the shank 36.

The feeding of the material is accomplished by the knife 61 when it has penetrated about one-half the thickness of the material at which time the lateral movement of the knife occurs carrying the sole and shoe with it to its new position. The length of feed is slightly less than the width of the chisel knife 61 so that by a continuation of movements a continuous cut is made through the sole, the edge of which, after the cut has been made, conforming to the edge of the welt.

This makes a very effective device for rough rounding the sole of the shoe, and at the same time cutting a channel in the under face thereof.

It is believed that the operation and many

advantages of this invention will be fully understood from the foregoing description.

Having thus described my invention, I claim:

5. 1. In a machine of the class described, the combination of a work support; a presser foot coacting therewith; a channeling knife on said work support; an operating table; a reciprocating chisel knife coacting therewith; and means for moving said work support and channeling knife transversely of said chisel knife.

10. 2. In a machine of the class described, the combination of a work support; a presser foot coacting therewith; an operating table; a reciprocating chisel knife coacting therewith; and means for moving said work support transversely of said chisel knife while the latter is in the work.

15. 3. In a machine of the class described, the combination of a frame; a member mounted therein and adapted to be reciprocated transversely thereof; a work support secured thereto and movable therewith; a presser foot; a chisel knife adapted to be reciprocated perpendicularly to the face of said work support; an operating table coacting therewith; and cam mechanism for moving said reciprocating member while the chisel

20. 4. In a machine of the class described, the combination of a frame; a member mounted therein and adapted to be reciprocated transversely thereof; a work support secured thereto and movable therewith; a presser foot; a chisel knife secured thereto; a channeling knife secured thereto; a presser foot; a chisel knife adapted to be reciprocated perpendicularly to the face of said work support; an operating table coacting therewith; and cam mechanism for moving said reciprocating member while the chisel knife is in the work.

25. 5. In a machine of the class described, the combination of a frame; a member mounted therein and adapted to be reciprocated transversely thereof; an oscillating work support secured thereto and movable therewith; a presser foot; a chisel knife adapted to be reciprocated perpendicularly to the face of said work support; an operating table coacting therewith; and cam mechanism for moving said reciprocating member while the chisel knife is in the work.

30. 6. In a machine of the class described, the combination of a frame; a member mounted therein and adapted to be reciprocated transversely thereof; a work support consisting in part of a block mounted in said member; a second block clamped to the first block; a channeling knife interposed between said blocks with a cutting edge above the upper faces thereof; a presser foot; a chisel knife adapted to be reciprocated perpendicularly to the face of said work support; an operating table coacting therewith;

and cam mechanism for moving said reciprocating member while the chisel knife is in the work.

35. 7. In a machine of the class described, the combination of a frame; a member mounted therein and adapted to be reciprocated transversely thereof; a work support consisting in part of a block having a cylindrical shank mounted in said member; a second block clamped to the first block; a channeling knife interposed between said blocks with a cutting edge above the upper faces thereof; a pin radiating from said shank; a shouldered recess in said reciprocating member to limit the oscillation of said pin; a presser foot; a chisel knife adapted to be reciprocated perpendicularly to the face of said work support; an operating table coacting therewith; and cam mechanism for moving said reciprocating member while the chisel knife is in the work.

40. 8. In a machine of the class described, the combination of a frame; a member thereon movable transversely thereof; a lever pivotally secured thereto and reciprocable therewith; a work support extending laterally from the forward end of said lever; a presser foot; an operating table; a reciprocating chisel knife movable perpendicularly to the upper face of said work support; and cam mechanism for imparting transverse movement to said movable member while the chisel knife is in the work.

45. 9. In a machine of the class described, the combination of a frame; a member thereon movable transversely thereof; a lever pivotally secured thereto and reciprocable therewith; a work support extending laterally from the forward end of said lever; a channeling knife secured thereto with its cutting edge above the upper face thereof; a presser foot; an operating table; a reciprocating chisel knife movable perpendicularly to the upper face of said work support; and cam mechanism for imparting transverse movement to said movable member while the chisel knife is in the work.

50. 10. In a machine of the class described, the combination of a frame; a member thereon movable transversely thereof; a lever pivotally secured thereto and reciprocable therewith; a work support extending laterally from the forward end of said lever; a presser foot; an operating table; a reciprocating chisel knife movable perpendicularly to the upper face of said work support; cam mechanism for imparting transverse movement to said movable member while the chisel knife is in the work; a stop member on the frame; and a spring for retaining said lever normally against said stop member.

55. 11. In a machine of the class described, the combination of a frame; a member thereon movable transversely thereof; a lever pivotally secured thereto and reciprocable there-

with; a work support extending laterally from the forward end of said lever; a presser foot; an operating table; a reciprocating chisel knife movable perpendicularly to the upper face of said work support; cam mechanism for imparting transverse movement to said movable member while the chisel knife is in the work; a stop member on the frame; a spring for retaining said lever normally against said stop member; and means for regulating the tension of said spring.

12. In a machine of the class described, the combination of a frame; a cylindrical member therein movable transversely thereof; a lever eccentrically pivoted to an end thereof and reciprocable therewith; a work support extending laterally from the forward end of said lever; a presser foot; an operating table; a reciprocating chisel knife movable perpendicularly to the upper face of said work support; cam mechanism for imparting transverse movement to said movable member while the chisel knife is in the work; and means for moving said cylindrical member about its axis.

13. In a machine of the class described, the combination of a frame; a cylindrical member therein movable transversely thereof; a lever eccentrically pivoted to an end thereof and reciprocable therewith; a work support extending laterally from the forward end of said lever; a presser foot; an operating table; a reciprocating chisel knife movable perpendicularly to the upper face of said work support; cam mechanism for imparting transverse movement to said movable member while the chisel knife is in the work; and an arm for moving said cylindrical member about its axis.

14. In a machine of the class described, the combination of a frame; a cylindrical member therein movable transversely thereof; a lever eccentrically pivoted to an end thereof and reciprocable therewith; a work support extending laterally from the forward end of said lever; a presser foot; an operating table; a reciprocating chisel knife movable perpendicularly to the upper face of said work support; cam mechanism for imparting transverse movement to said movable member while the chisel knife is in the work; an arm for moving said cylindrical member about its axis; and a stop member against which said arm normally rests.

15. In a machine of the class described, the combination of a frame; a cylindrical member therein movable transversely thereof; a lever eccentrically pivoted to an end thereof and reciprocable therewith; a work support extending laterally from the forward end of said lever; a presser foot; an operating table; a reciprocating chisel knife movable perpendicularly to the upper face of said work support; cam mechanism for imparting transverse movement to said

movable member while the chisel knife is in the work; means for moving said cylindrical member about its axis; and means for moving said lever about its pivot on said cylindrical member.

16. In a machine of the class described, the combination of a frame; a cylindrical member therein movable transversely thereof; a lever eccentrically pivoted to an end thereof and reciprocable therewith; a work support extending laterally from the forward end of said lever; a presser foot; an operating table; a reciprocating chisel knife movable perpendicularly to the upper face of said work support; cam mechanism for imparting transverse movement to said movable member while the chisel knife is in the work; means for moving said cylindrical member about its axis; and a pivoted member provided with a toe normally engaging said lever and adapted to coact therewith to move it about its pivot on said cylindrical member.

17. In a machine of the class described, the combination of a frame; a cylindrical member therein movable transversely thereof; a lever eccentrically pivoted to an end thereof and reciprocable therewith; a work support extending laterally from the forward end of said lever; a presser foot; an operating table; a reciprocating chisel knife movable perpendicularly to the upper face of said work support; cam mechanism for imparting transverse movement of said movable member while the chisel knife is in the work; means for moving said cylindrical member about its axis; and a pivoted member provided with a toe normally engaging said lever and adapted to move it about its pivot on said cylindrical member and also provided with means for simultaneously moving said presser foot about its pivot.

18. In a machine of the class described, the combination of a frame; a pivoted lever carrying a work support; a pivoted presser foot coacting therewith; an operating table; a reciprocating chisel knife coacting therewith; and means for simultaneously moving said work support and presser foot about their pivots in opposite directions.

19. In a machine of the class described, the combination of a frame; a pivoted lever carrying a work support; a pivoted presser foot coacting therewith having a rearwardly curved arm; an operating table; a reciprocating chisel knife coacting therewith; and a pivoted lever having lateral projections engaging with the curved arm of said presser foot and said work support lever.

20. In a machine of the class described, the combination of a frame; a pivoted lever carrying a work support; a pivoted presser foot coacting therewith; a cylindrical stud mounted in the frame to the end of which said presser foot is eccentrically pivoted;

means for moving said stud about its axis; an operating table; a reciprocating chisel knife coacting therewith; and means for simultaneously moving said work support 5 and presser foot about their pivots in opposite directions.

21. In a machine of the class described, the combination of a frame; a pivoted lever carrying a work support; a pivoted presser foot coacting with said work support; a cylindrical stud mounted in the frame to the end of which said presser foot is eccentrically pivoted; means for moving said stud about its axis; means for creating a friction 15 on said stud to retain it in adjusted position; an operating table; a reciprocating chisel knife coacting therewith; and means for simultaneously moving said work support and presser foot about their pivots in 20 opposite directions.

22. In a machine of the class described, the combination of a frame; an operating table thereon; a reciprocating chisel knife coacting therewith; a work support movable 25 transversely of said chisel knife; a presser foot coacting with said support; and means for adjusting the position of said support

and presser foot toward and from the front face of said knife.

23. In a machine of the class described, 30 the combination of a frame; an operating table thereon; a reciprocating chisel knife coacting therewith; a work support movable transversely of said chisel knife; a channeling knife secured to said support 35 and movable therewith; a presser foot coacting with said support; and means for adjusting the position of said support and presser foot toward and from the front face 40 of said knife.

24. In a machine of the class described, the combination of a frame; an operating table thereon; a reciprocating chisel knife coacting therewith; a work support movable 45 transversely of said chisel knife; a presser foot coacting with said support; means for adjusting the position of said support and presser foot toward and from the front face of said knife; and means for moving said 50 work support transversely of said chisel knife while the latter is in the work.

Signed by me at Boston, Mass., this 25th day of March, 1915.

LAWRENCE E. JOHNSON.
